CIGARETTE MAKING DEVICE

Michele Celucci, New York, N. Y.

Application July 29, 1939, Serial No. 287,279

6 Claims. (Cl. 131—58)

This invention relates to pencil-size cigarette making devices which can be carried removably attached to one's clothing.

One of the objects is to provide a device which mechanically shapes and rolls a cigarette by removably locking the cigarette paper in the device and providing cooperative relatively turnable tubular means for shaping the paper and holding the tobacco therewithin and having means for ejecting the manufactured cigarette.

Other objects are to provide means in such a device for packing or ramming the tobacco into the ends of the formed cigarette; to provide means in such a device for removably clasping the device to a person's clothing; to provide a door entry to the interior for entry of cigarette paper, tobacco and moistening means to seal the cigarette paper.

Still another object is to provide such a device with means for permanently or removably mounting same in a cigarette case.

These and other objects are accomplished as explained in the following description and accompanying drawing forming part thereof.

In the drawing,

Fig. 1 is a longitudinal plan view of the device showing the door open and the forward ram plug removed from the device.

Fig. 2 is a perspective view showing a piece of cigarette paper inserted in the paper slots of the inner turnable tube.

Fig. 3 is a cross section view taken on line 3—3 of Fig. 1, but showing the paper having an end now folded over the slotted arm portion of the inner tube and showing tobacco in the paper and the free end of the paper extending thru the door and outside the device, the paper and inner tube having been moved from the position of Fig. 2, to that of Fig. 3, the inner tube having been turned in the direction of curved arrow of Fig. 3, by means of its end knob.

Fig. 4 is a cross section view taken on line 4—4 of Fig. 1, showing the paper now turned completely around the tobacco after having its free glue containing end moistened and pressed down on the lower portion of curled paper, the inner tube having been turned in the direction of curved arrow of Fig. 4.

Fig. 5 is a longitudinal section view of the device showing the right ram rod bearing against one end of the completed cigarette, the cigarette having been partly ejected from the device.

Fig. 6 shows a pencil stub mounted in the left-hand ram.

Fig. 7 is a perspective view of split tube spring member 15.

An outer tube 10, has a door 11 hinged thereon at 12 providing a closure for doorway 13. Said door hinge may be spring actuated as by member 111 tending to normally close the door. At the right end 101, of tube 10, an inner and slotted tube 14, is turnably mounted being held in position by means of split tube spring member 15 or the like means said spring normally flexing against the inner surface of the outer tube. A threaded end 16 is provided to cooperate with similar threads 17 on inner portion of knob 18. A bushing 19 slidably mounts rod 20 having handle 21 and long ram 22 at opposite ends. Member 21 has threads 31 which cooperate with threads 17 to removably lock the ram rod with the knob when the parts are inoperative. The inner tube has a longitudinal segment 141 therefrom removed to provide for passageway P for a length of cigarette paper 23 and preferably long fine grain cut tobacco T therethrough. (See top of inner tube at Fig. 3.) A longitudinal slot 25 which may be slightly longer than a length of cigarette paper, is provided in the inner tube. There is thus provided on said inner tube a transverse arcuate longitudinal arm 26, having a narrow slot 25 at one of its sides and a substantial space or wide slot, providing a passageway P, at its other side.

The left end 102 of said tube may receive there-in slidably fitting ram 27, removably fastened to member 10 by means of chain 28 or the like. A pencil 29 or the like may be removably and reversibly mounted in member 27 so that unpointed end 291 acts as a ram and pointed lead end 292 acts as a pencil (see Fig. 6).

A clasp 31 having sleeve 311, similar to a fountain-pen clasp, provides means for clasping the device to the clothing of a person. Said clasp is turnably mounted on the outer tube and may be turned to suitably hold the door 11 in closed position in the embodiment in which member 11 has no spring normally closing said member.

In operation to make a cigarette the arm 26 is registered with the doorway 13 and paper 23 is placed in slot 25 (see Fig. 2). The arm 26 thru the medium of knob 18, is then turned in the direction of curved arrow of Fig. 2, and end 231 of paper is folded down into the inner tube and against the inner side of arm 26. The inner tube's wide slot P is now registered with doorway 13 of outer tube providing passageway for tobacco T therethru which on being pressed into the tube 14 causes paper 23 to take the shape of

the inner wall of the tube. The inner tube is then turned in direction of curved arrow of Fig. 4, and the paper is seen to wind itself around the tobacco and to form a lap as seen at top of member 26, Fig. 4. The glue-containing end surface of the paper is moistened and then glued to lower portion of the paper. The cigarette now formed is then tamped at its ends by means of rams 22, 291. Member 27 is then removed from outer tube and the cigarette, now completely made, is pushed to the left and out of the device by means of long ram 22 attached to rod 20.

Parts may be used without others. The disclosure is intended to be illustrative rather than limitative.

I claim:

1. A cigarette making device comprising an outer tubular member having a cutaway portion providing to said outer member a semi-cylindrical portion and cylindrical end portions, an inner tube member having a transversely arcuate longitudinal arm at one of its ends and a tube slot at each side of said arm, said inner tube being rotatably mounted in an end of the outer tubular member, yieldable means, separable from the tubes, flexing against the inner wall surface of the outer tube, a stop on the inner tube abutting said yielding means to facilitate holding said inner tube within the outer tube, said slots and arm being turnably registerable with said cutaway portion.

2. The device of claim 1 including a plunger means slidably mounted within the inner tube for longitudinal movement therethrough.

3. The device of claim 1 including a sliding plunger mounted at each end thereof.

4. A cigarette making device comprising an outer tubular member having a cutaway portion providing to said outer member a semi-cylindrical portion and cylindrical end portions, an inner tube member having a transversely ar-

cuate longitudinal arm at one of its ends and a tube slot at each side of said arm, said inner tube being rotatably mounted in an end of the outer tubular member, yieldable means, separable from the tubes, flexing against the inner wall surface of the outer tube, a stop on the inner tube abutting said yielding means to facilitate holding said inner tube within the outer tube, said slots and arm being turnably registerable with said cutaway portion, a knob means at one end of the inner tube for rotating said tube, a plunger slidably mounted within the inner tube, and cooperative means on the plunger and knob to removably lock them together.

15 5. The device of claim 4 including a door hingedly mounted on the outer tube covering said cutaway portion and spring means on the door normally urging the door to closed position.

6. A cigarette making device comprising an outer tubular member having a cutaway portion providing to said outer member a semi-cylindrical portion and cylindrical end portions, an inner tube member having a transversely arcuate longitudinal arm at one of its ends and tube slot at each side of said arm, said inner tube being rotatably mounted in an end of the outer tubular member, yieldable means, separable from the tubes, flexing against the inner wall surface of the outer tube, a stop on the inner tube abutting said yielding means to facilitate holding said inner tube within the outer tube, said slots and arm being turnably registerable with said cutaway portion, a knob means at one end of the inner tube for rotating said tube, a plunger slidably mounted within the inner tube, cooperative means on the plunger and knob to removably lock them together, a door hingedly mounted on the outer tube covering said cutaway portion, and a clasp mounted on the outer tube to removably hold the device on an article.

MICHELE COLUCCI.
